Primary Examiner—Nanda Bondade

(74) Attorney, Agent, or Firm—Thomas I. Rozsa; Tony D. Chen; Jerry Fong

(57) CLAIM

The ornamental design for an entertainment and communication device for furniture, as shown and described.

DESCRIPTION

FIG. 1 is a perspective view of an entertainment and communication device showing my new design;

FIG. 2 is a front view of the entertainment and communication device on the right side, shown separately for clarity of illustration;

FIG. 3 is a right side view thereof; and,

FIG. 4 is a bottom plan view thereof.

The broken line showing on FIGS. 1 and 2 is for illustrative purposes only and forms no part of the claimed design.
